UNITED STATES PATENT OFFICE.

DICKRAN M. SARKISIAN, OF MALDEN, MASSACHUSETTS.

SASH-CURTAIN FRAME.

No. 904,091.

Specification of Letters Patent.

Patented Nov. 17, 1908.

Application filed February 26, 1908. Serial No. 417,802.

To all whom it may concern:

Be it known that I, DICKRAN M. SARKISIAN, a citizen of the United States, and resident of Malden, county of Middlesex,

5 State of Massachusetts, have invented an Improvement in Sash-Curtain Frames, of which the following description, in connection with the accompanying drawing, is a specification, like letters on the drawing representing like parts.

10 This invention has for its object the production of a simple and strong frame for sash-curtains, so constructed and arranged that the making of the frame is made easier 15 and it can be readily fitted into the opening of a window sash.

Sash-curtains are now held in position in various ways, one very common arrangement consisting of rods attached to the top and 20 bottom of the sash by small brackets, the curtain being mounted on the rods. This device requires considerable care in its application, for if the rods are not just the right length, or the brackets are spaced apart in 25 correctly they will not coöperate with the rods, and the brackets must be fastened in place by means of small screws.

In my present invention I provide four 30 corner-pieces, channeled to receive the top, bottom and side bars of the frame, and so arranged that if a bar is not cut just the right length it may still be used, each corner-piece having means to prevent the ends of 35 bars at right angles to each other from interfering.

In my preferred form of construction the bars are flat, and the frame rests within the opening of the sash, against or adjacent the glass, and is held in place by suitable means, 40 as screw-eyes, which can be given a part turn when it is desired to remove the sash-curtain.

Figure 1 is an inner front elevation of a window sash with a curtain frame applied thereto embodying my invention, the sides, 45 top and bottom of both the sash-curtain frame and the sash being broken out to save space; Fig. 2 is an enlarged view of one of the corner-pieces of the curtain frame, showing the means for preventing interference of 50 the ends of adjacent bars; Fig. 3 is a cross-section thereof on the line 3—3, Fig. 2. Fig. 4 is a perspective detail of the corner of one of the corner pieces.

55 In Fig. 1 a window sash of any usual construction is shown, comprising the lower

60 rail 1, upper or meeting rail 2, and the side rails 3, fixedly connected in any suitable manner and in practice carrying a pane of glass in the opening.

65 In accordance with my invention the sash-curtain comprises four corner-pieces and connecting bars detachably mounted on them, the sash-curtain being supported on the top and bottom bars of the frame.

70 One of the corner-pieces is shown enlarged in Fig. 2, and in practice is made of sheet metal, of substantially L-shape in plan, the longitudinal edges of the arms 4, 4 being flanged at 5 and inturned at 6, Fig. 3, to 75 form two intersecting channels on the face of the corner-piece.

75 A diagonal shoulder or stop 7 is made in the angle of the corner-piece, (see Figs. 1, 2, and 4) the shoulder crossing the bottoms 80 of the two channels at their intersection, for a purpose to be described.

80 Flat and preferably metallic bars 8 and 9 are connected with the corner-pieces by sliding an end of each bar into one of the channeled arms, the bars 8 being at the top and bottom of the frame and the bars 9 at the sides thereof, as in Fig. 1. The bars are cut to substantially the proper length, but as 85 they are slidable in the channeled arms and held therein frictionally it is not necessary to cut the bars exactly accurate, as the length of the arms 4 of the corner-pieces permits some leeway in fitting, as will be manifest. As the backs of the corner-pieces are 90 flat they will rest squarely upon the pane of glass, in the corners of the sash, and the frame can be held in place by screw-eyes 10 in the side rails of the window sash, Fig. 1, 95 which can be turned into dotted line position when it is desired to remove the frame.

The sash-curtain C is shown in part only in Fig. 1, and is mounted on the top and bottom bars by means of hems, through 100 which the bars are run.

105 By the device shown the curtain is brought close to the glass, it can be easily applied or removed, and to put up one of the frames no skilled labor is required.

110 To prevent the ends of the adjacent bars 8 and 9 connected by a corner-piece from interfering I provide each corner-piece with the diagonal shoulder or stop 7, which is raised slightly above the bottom of the intersecting portions of the channels, this shoulder preventing the end of a bar from passing into the angle of the corner-piece.

Thus neither of the two bars can interfere with the other, and any distortion of the frame is prevented.

Having fully described my invention, 5 what I claim as new and desire to secure by Letters Patent is:—

1. A sash-curtain frame comprising L-shaped corner-pieces having their longitudinal edges flanged and inturned to form 10 channels on the face of the corner-pieces, a diagonal stop crossing the angle of each corner-piece and flat connecting bars slidable into the channels, the stop in each corner piece preventing the projection of the end 15 of either bar into the path of the other bar.

2. As a new article of manufacture, an L-shaped corner-piece for sash-curtain frames, made of sheet metal and having its longitudinal edges flanged and overturned, to form intersecting channels on the face of the corner-piece, and having also a diagonal shoulder crossing the bottoms of the channels at their intersection and forming a stop. 20

In testimony whereof I have signed my name to this specification in the presence of 25 two subscribing witnesses.

DICKRAN M. SARKISIAN.

Witnesses:

JOHN C. EDWARDS,

THOMAS J. DRUMMOND.
